AUTOMATIC CLOTHES CLEANSING APPARATUS

Peter Eduard Geldhof and Luther Ringer, St. Joseph, Mich., assignors to Nineteen Hundred Corporation, St. Joseph, Mich., a corporation of New York

Application February 21, 1944, Serial No. 523,238

4 Claims. (Cl. 68—12)

1

The present invention relates to an automatic cleansing apparatus or the like with which are associated storage facilities for the temporary storing of the cleansing fluid between certain stages in the operating cycle of the cleansing apparatus.

More particularly, the present invention is concerned with an automatic, washing, rinsing and drying machine having in combination therewith suitable storage facilities for the temporary handling of the water to store and reheat the water supply pending the completion of additional operating steps in the cycle of operations of the automatic washing, rinsing and drying machine.

The present invention is particularly advantageously adapted to use in connection with laundering operations in which the articles to be laundered are subjected to a washing operation in an automatic washing, rinsing and drying apparatus in which heated water is employed containing soap and other suitable detergents for the furtherance of the laundering operation. It is highly desirable to save the prepared soapy water for the performance of other laundering operations while the additional steps of rinsing and drying the first batch of laundered articles are taking place.

It is also desirable in such operations to raise the temperature of the soapy water while it is being stored in order that more effective laundering of the subsequent batches of articles to be laundered will be assured. Inasmuch as the laundering apparatus performs a series of operations in accordance with a predetermined operating cycle, it is highly advantageous to have whatever storage facilities are employed to augment the laundering apparatus closely related to and regulated by the control mechanism employed in the operation of the laundering apparatus.

While the apparatus of the present invention is capable of employment in a wide variety of fluid handling operations, it is particularly well adapted to use with an automatic washing, rinsing and drying machine and will, therefore, for the sake of clarity but in no sense of limitation, be described in its adaptation to such equipment. As is customary in the use of such equipment, a complete cycle of operations is performed on a single batch of articles to be laundered including washing, rinsing and drying steps before any subsequent batches of laundry are introduced to the apparatus. The rinsing operations, of which there are ordinarily several, usually employ only clear water of relatively low or medium tem-

2

perature and, therefore, may be discharged to the drain in order that a fresh water supply may be employed for each of these operations.

In the case of the washing step, however, an abundance of water of relatively high temperature having large quantities of soap and other suitable cleansing agents therein is required. In the interest of saving both hot water and soap, it is, therefore, particularly advantageous to remove the soapy water from the container of the automatic washing, rinsing and drying machine following the washing step and temporarily storing it until the remaining steps in the cycle of operations all of which are performed in or with the aid of the container of the machine are completed. The soapy water employed in the first washing step may again be introduced to the container for re-use upon the completion of the remaining steps in the laundering operation.

20 Such a procedure as that outlined makes possible a considerable saving in the hot water supply and also in the quantity of detergents required to complete the laundering operations. This saving of the hot water supply is particularly important under conditions where water is scarce or where the heating system is incapable of producing a continuous supply of water at temperatures sufficiently high to perform the several washing steps for numerous batches of laundry.

25 It is, therefore, an object of the present invention to provide means capable of producing the aforementioned advantageous results and, in so doing, to facilitate the use of the automatic washing, rinsing and drying apparatus.

30 It is a further object of the present invention to provide a fully automatic cleansing apparatus with which is associated a suitable fluid reservoir for temporarily storing the cleansing fluid employed in the apparatus between certain stages in the operating cycle thereof.

35 It is a still further object of the present invention to provide a suitable fluid storage means which is capable of being connected into the control mechanism for operation in conjunction with the apparatus employing the fluid to facilitate the automatic operation of the unit.

40 Another object of the present invention is to provide a suitable fluid storage means comprising a fluid reservoir having heating means or the like therein for changing the temperature of the fluid during the period of its storage in the reservoir and means for controlling the level of the fluid in said reservoir as well as the operation of the heating means.

45 Another and still further object of the present

invention is to provide a fluid operated control means for a fluid reservoir to control the level of the fluid in the reservoir and to actuate certain other elements of the apparatus associated with the fluid reservoir such, for example, as heating means and the like.

It is a still further object of the present invention to provide a complete control unit for operating an automatic washing, rinsing and drying machine together with the temporary storage means associated therewith for handling the storage of the cleansing fluid from the machine pending the completion of certain of the steps in the cycle of operation of the machine.

On the drawings:

Figure 1 is a plan of a typical form of automatic washing, rinsing and drying machine with which is associated a fluid storage means to provide a combination embodying the principles of the present invention;

Figure 2 represents an elevation of the apparatus of Figure 1 with parts removed and in section for the purpose of illustrating the cooperative relationship of the several elements comprising the apparatus of the invention;

Figure 3 is a vertical section through the fluid storage means with parts broken away and in elevation to illustrate one form of fluid storage apparatus of the type to which the present invention relates;

Figure 4 is a horizontal cross section taken along the line IV-IV in Figure 2;

Figure 5 is a partial sectional elevation through the reservoir of the fluid storage means of Figures 3 and 4 illustrating one form of fluid operated control means which is adapted to use in controlling the maximum fluid level in the reservoir of the storage means and the operation of the temperature changing apparatus thereof; and

Figure 6 is a diagrammatic representation of a typical electrical circuit for controlling the operation of an automatic washing machine embodying the fluid storage means according to the present invention.

As shown on the drawings:

In Figures 1 and 2 of the drawings, a typical form of automatic washing, rinsing and drying machine is designated by the reference character 10 and is highly advantageous in illustrating the application of the principles of the present invention. The washing machine 10 is provided with a cabinet 11 which includes a top panel 12 in which is disposed a cover 13 for facilitating the introduction of the articles to be laundered to the interior of the machine.

A control knob 14 for the purpose of setting or adjusting a suitable timing mechanism which directs the operation of the washing machine in the performance of the complete cycle of its operations is disposed adjacent one corner of the top panel 12 of the apparatus. The timer unit itself (not shown) is mounted in the cabinet 11 directly under the top panel 12. A second control knob 15 by means of which the operator may select the desired temperature for the cleansing fluid which is supplied by a suitable mixer type valve (not shown) to be employed in the laundering operation is positioned in another corner of the top panel 12 of cabinet 11.

The automatic washing machine 10 is generally of the type described and claimed in detail in our copending application Serial No. 491,618, entitled "Automatic washing, rinsing and drying machine," filed June 21, 1943.

The automatic washing machine 10 embodies a container or tub 17 (Figure 2) for the reception of the cleansing fluid from the aforementioned mixer valve unit which is adapted to provide water of a predetermined temperature from suitable supply sources of hot and cold water depending upon the setting of the control knob 15 in the top panel 12 of the cabinet 11 by the operator at the beginning of operations. A motor 18 mounted in the cabinet 11 of the washing machine 10 actuates a reciprocating agitator and a rotatable perforated drying basket (not shown) both of which are mounted in the tub 17 through a transmission 19 and any suitable driving connection with which is associated a plurality of automatically operated shifter mechanisms (not shown).

The motor 18 also actuates a pump 20 the intake side of which is connected as by means of the hose connection 22 to a sump 21 formed in the base of the tub 17. A hose connection 23 connects the outlet side of the pump to a suitable valve means 24 for handling the water discharged from the tub 17. The valve 24 advantageously takes the form of a two-way valve unit of the type described and claimed in our copending application Serial No. 513,138, entitled "Drain mechanism," filed December 6, 1943, now issued as Patent No. 2,414,196. The valve 24 is adapted to be automatically operated to direct the water discharged from the tub 17 by the pump 20 to a suitable storage means 25 through the hose connection 26 which is provided with a goose-neck 27 extending into the interior of the storage means or to a suitable drain (not shown) through the hose connection 28.

The storage means 25 has a cabinet 29 which serves to completely enclose the apparatus and is supported from the floor as by means of a plurality of adjustable feet 30. The cabinet 29 of the storage means 25 is provided with a top panel 31 in which is disposed a cover 32 which affords access to the interior of the storage means 25. A fluid reservoir 33 is supported within the cabinet 29 as by means of the cross member 34.

One wall of the cabinet 29 has an opening 35 therein fitted with a removable panel portion 36 which is apertured to receive and support the goose-neck 27 of the hose connection 26 extending through an aperture 37 into the fluid reservoir 33 of the storage means 25. The base of the fluid reservoir 33 is advantageously sloped in all directions toward a drain outlet 38 therein which registers with an aperture in the cross member 34 and is provided with a suitable screen 39 to prevent foreign matter from entering the connection 40 to which the pump 41 is attached for support from the cross member 34. The pump 41 which is driven as by means of a motor 42 is adapted to withdraw the water from the reservoir 33 of the storage means 25 and discharge the same through the hose connection 43 into the container 17 of the automatic washing machine 10 through a suitable connection 44 to which said hose 43 is attached.

A suitable fluid control mechanism 46 (see Figure 5) is secured to one wall of the fluid reservoir 33 and is adapted to determine the maximum level of fluid in the reservoir 33 as well as to operate the heating element 47 for reheating the water supply when the water level in the reservoir has risen to the desired point. The fluid control mechanism 46 includes an arm 48 which extends through an aperture 49 in one wall of the

fluid reservoir 33 and is pivoted thereon as at the support 50. On one end of the arm 48 is secured a ball float 51.

The end of the arm 48 opposite the float 51 projects through a flexible member or boot 52 which is held in place on the external wall of the fluid reservoir 33 as by means of a ring 53 and cooperating seals so as to close off the aperture 49 through which the arm 48 extends. The end of the arm 48 projecting through the boot 52 is threaded and is adapted to receive a plurality of nuts 54 which cooperate with suitable washers and sealing means to make a tight joint with the boot 52 at the point where the arm 48 extends therethrough. A bracket 55 is mounted upon the threaded end of the arm 48 in any suitable fashion and is connected as by means of a link 56 with the arm 57 of a toggle switch 58 secured as by means of a bracket 59 to the outer wall of the fluid reservoir 33 at a point substantially directly below the aperture 49 therein.

A suitable multiple wire cable 60 extends through a grommeted aperture in the wall of the cabinet 29 of the storage means 25 to provide the necessary electrical connections for the heating element 47, the toggle switch 58, and the motor 42. The other end of the cable 60 is provided with a conventional plug or male fitting (not shown) which is adapted to be plugged into a corresponding female receptacle on the cabinet 11 of the automatic washing machine 10 in order that the operating and control circuits for the washing machine and for the storage means 25 will be satisfactorily interrelated to operate both units in accordance with a predetermined cycle of operations.

The storage means 25 has a three pole double throw switch 61 mounted upon the wall of its cabinet 29 in a suitable recess 62 therein for controlling the operation of the storage means 25 to independently shut the same off when desired. A pilot light 63 may also be provided in the recess 62 to indicate to the operator that the storage means 25 is operatively connected to the control circuit for the automatic washing machine 10 and that the reservoir 33 is filled with water which is being heated.

The operation of the storage means 25 and its cooperative relationship with the automatic washing machine 10 will be best understood by reference to the control circuit which is diagrammatically represented in Figure 6 of the drawings.

The timer unit 65 which is illustrated diagrammatically in Figure 6 of the drawings is operated from the control knob 14 in the top panel 12 of the cabinet 11 for the automatic washing machine 10. The timer 65 advantageously includes a plurality of cam disks 66 to 71, inclusive, mounted on a shaft 72 extending therethrough and actuated by a motor 73 in a step-by-step action at sixty second intervals. More specifically, the construction of the timer 65 is such that the shaft 72 is advanced through an angle of approximately 8° every sixty seconds.

All of the several cam disks 66 to 71, inclusive, are rotated by the shaft 72 in the direction indicated by the arrows. The cams 66 to 71, inclusive, cause their respective movable contact arms 75 to 80, inclusive, each of which is provided with a cam follower in engagement with one of said cams, to make and break contact with their respective fixed contacts 82 to 87, inclusive as the followers trace the peripheries of said cams.

The operation of the timer unit 65 is, there-

fore, to cause the making and breaking of a plurality of electrical circuits each of which is connected through operating elements of both the automatic washing machine 10 and the storage means 25. This function of the timer affords a predetermined cycle of operations of a duration dictated within certain predetermined limits by the wishes of the operator in the setting of the timer control knob 14. A switch 88 embodying a disk mounted on the shaft 72 of the timer unit 65 and a pair of fixed contacts associated therewith enables the adjustment of the timer unit within certain predetermined ranges of operation.

15 The water temperature control switch 90 which is adapted to be manually set by the control knob 15 provided in the top panel 12 in the cabinet 11 of the automatic washing machine 10 comprises a rotatable shaft 91 on which are mounted disks 92 and 93 for selectively securing a water supply of any of several different temperatures for the tub 17 of the automatic washing machine. The temperature control switch 90 illustrated in diagrammatic form in Figure 6 of the drawings 20 is adapted to provide water of three different temperatures depending upon the setting of the disks 92 and 93 with respect to the movable contact arms 94 and 95, respectively, associated therewith. With the setting of the control knob 25 15 and the shaft 91 shown, the temperature control switch 90 will actuate both solenoids V1 and V2 of a mixer valve (not shown) to produce a mixed water supply by virtue of the contact of the movable contact arms 94 and 95 with their respective fixed contacts 96 and 97.

For a complete understanding of the operation of the apparatus of the present invention, it will not be necessary to trace through each of the individual operating circuits shown in Figure 6. 40 The operation of the automatic washing machine is generally similar to that described in detail in our aforementioned application Serial No. 491,618. The timer control unit illustrated in Figure 6 differs from that of the application in question primarily in that it employs a separate cam disk to control the making and breaking of each individual circuit.

Let us assume for the purpose of the present explanation that the timer control knob 14 has 45 been adjusted by the operator in the manner indicated in Figure 6 such that the contact arms 76, 78 and 79 associated with cam disks 67, 69 and 70 of the timer unit 65 are in contact with their respective fixed contacts 83, 85 and 86. At the start of the operations, the operator also sets the control knob 15 adjusting the temperature control mechanism 90 to provide water of a desired temperature when the mixer valve is actuated in its proper sequence in the cycle of operations 50 controlled by the timer unit 65. When the control knob 14 for the timer unit 65 is set to start the operation of the automatic washing machine 10, the switch 61 on the storage means 25 is in its downward position as indicated by the full lines in Figure 6 so that each of its three poles will be 55 in contact with the fixed contacts 98, 99 and 100.

With these conditions fulfilled, the circuits through the solenoids V1 and V2 for the mixer valve unit supplying water to the tub 17 are 60 energized and water at a temperature provided in accordance with the setting of the temperature control switch 90 is introduced. The electrical current for energizing the solenoid V1 is supplied from the main power conduit 101 through conductors 103 and 104 to one side of solenoid V1

being completed through conductor 105 on the other side of said solenoid, fixed contact 86 and movable contact arm 94 of the temperature control switch 90, conductor 106, arm 107 and fixed contact 99 of the switch 61, conductor 108, fixed contact 83, movable contact arm 76, conductors 109 and 110, fixed contact 111 for the top float switch 112 of a fluid level control means 113, conductor 14, the switch 88, and conductor 115 with the main power conduit 102. The solenoid V2 is energized by electrical current supplied from main power conduit 101, conductors 103 and 116 to one side of said solenoid while the other side is connected with the other main power conduit 102, through conductor 111, fixed contact 87 and movable contact arm 95 of the temperature control switch 90, conductor 118, fixed contact 98 and movable arm 119 of the switch 61, conductor 120, fixed contact 85, movable contact arm 78, conductors 121 and 110, fixed contact 111 for the top float switch 112, conductor 114, switch 88 and conductor 115.

As the tub 17 of the automatic washing machine 10 is filled, the bottom float switch 122 of the fluid level control means 113 will break contact with its fixed contact point 123. The top float 112 will break contact with its fixed contact 111 when the water has reached the desired level in the tub 17 and thereafter makes contact with the fixed contact 124. The breaking of the contact of the top float switch 112 with its fixed contact 111 causes the deenergization of the solenoids V1 and V2 of the mixer valve and no further water will be added to the tub 17 unless through some inadvertent occurrence the water level should fall therein.

After the tub 17 has been filled and if the operator desires to re-use the water into which suitable detergents have been introduced for the completion of the washing step, it is now necessary to trip the switch 61 of the storage means 25. The switch elements thereafter occupy the upper position, as indicated by the dotted lines in Figure 6, so that the several arms 107, 119 and 125 will thereafter be in contact with fixed contacts 126, 127 and 128, respectively.

The making of the contact between the top float switch 112 of the fluid level control means 113 with its fixed contact 124 completes the circuit through the solenoid A which serves to actuate the driving means for the agitator element of the automatic washing machine 10. At the same time, the circuits for the operation of the automatic washing machine motor 18 and the timer motor 73 are completed.

The circuit providing electrical current for the automatic washing machine motor 18 is completed from the main power conduit 101 through conductor 103 to one side of the motor and from the other side thereof to the main power conduit 102 through conductors 129, 130 and 131 with the fixed contact 124 for the top float switch 112, conductor 114, switch 88 and conductor 115. The timer motor 73 is energized to rotate the shaft 72 of the timer 65 by electrical current supplied from the main power conduit 101 through conductors 103 and 132 to one side of said motor and from the other side to the main power conduit 102 through conductors 130 and 131, fixed contact 124 for the top float switch 112, conductor 114, switch 88 and conductor 115.

While the timer motor 73 continues to advance the shaft 72 of the timer unit 65, the cam follower for the movable contact arm 79 is tracing a low point on the cam 70 and thereby main-

tains contact with its fixed contact 86 so as to energize the agitator solenoid A until the shaft 72 of the timer unit has rotated the cam 70 so as to cause the movable contact arm 79 to break contact with its fixed contact 86. In the meanwhile, the circuit through the agitator solenoid A is completed from the main power conduit 101 through conductors 103 and 133 to one side thereof while the other side is connected with the main power conduit 102 through conductor 134, fixed contact 86, movable contact arm 79, conductor 131, fixed contact 124 for the top float switch 112, conductor 114, switch 88 and conductor 115.

At the completion of the washing step, the shaft 72 of timer 65 will have rotated to the point at which the followers for the several movable contact arms 76, 78 and 79 will have traced the low points on their respective cams 67, 69 and 70 and the contact will be broken with fixed contacts 83, 85 and 86. At this point, the followers for the movable contact arms 75 and 80 will drop off into the low points on their respective cams 66 and 71 thereby establishing contact with fixed contacts 82 and 87 therefor. It will be apparent that the closing of the contact between the movable contact arm 75 and its fixed contact 82 affords an alternate circuit for the automatic washing machine motor 18 and the timer motor 73 from the main power conduit 101 through their original connections with that conduit and through conductor 135, fixed contact 82, movable contact arm 78, conductors 136 and 110, fixed contact 111 for the top float switch 112 after the water level drops in tub 17, conductor 114, switch 88 and conductor 115 to the other main power conductor 102.

This auxiliary circuit for the washing machine motor 118 and the timer motor 73 is necessary by reason of the fact that when the movable contact arm 80 makes contact with its fixed contact 87 an electrical circuit is completed through the pump solenoid P causing the pump to operate to withdraw the water from the tub 17 of the automatic washing machine 10. An electrical circuit is completed to one side of the pump solenoid P from the main power conduit 101 through conductors 103 and 137 and from the other side thereof through conductors 138 and 139, fixed contact 87, movable contact arm 80, conductor 114, switch 88 and conductor 115 with the other main power conductor 102.

Connected in as a part of the same circuit with the pump solenoid P is a similar solenoid B which operates the two-way valve 24 associated with the automatic washing machine 10 to cause the water passing through the pump 20 and into the discharge hose connection 23 to pass through the hose connection 26 and goose-neck 27 into the fluid reservoir 33 of the storage means 25. The electrical circuit is completed through the solenoid B for the two-way valve 24 from the main power conduit 101 through conductor 103 to one side of said solenoid and from the other side thereof to the other main power conduit 102 through conductor 140 fixed contact 128 and contact arm 125 for the switch 61, conductor 141, contacts 142 and 143 associated with the fluid operated control mechanism 46 for the storage means 25 by virtue of the fact that the float 51 is in its lowermost position, conductors 138a (a branch of conductor 138) and 139, fixed contact 87, movable contact arm 80, conductor 114, switch 88 and conductor 115.

The pump 20 withdraws all of the water from the tub 17 except that which is retained by the

laundry in the tub to the reservoir 33 of the storage means 25. The maximum water level within the fluid reservoir 133 required to raise the float 51 which actuates the fluid control mechanism 46 associated therewith is advantageously adapted to correspond substantially with the total quantity of the water admitted to the tub 17 of the automatic washing machine 10 so that, since some of the water is retained by the laundry contained in the tub, the float 51 will not be raised sufficiently to break contact with fixed contacts 142 and 143 of its toggle switch 58 when all of the free water has been withdrawn from the tub 17 by the pump 20.

After the pump 20 has withdrawn the water from the tub 17 of the automatic washing machine 10 to the storage means 25, the lower float switch 122 of the fluid level control means 113 will now make contact with its fixed contact 123 and an electrical circuit will be closed through the solenoid E which actuates the extractor for removing the water from the laundry in the automatic washing machine 10. The circuit is closed through the solenoid E from the main power conduit 101 through conductors 103 and 145 to one side of the solenoid and from the other side thereof through conductor 146, fixed contact 128 for the lower float switch 122, conductors 147, 138a and 139, fixed contact 81, movable contact arm 80, conductor 114, switch 88 and conductor 115 with the other main power conduit 102.

The operation of the extractor directly follows the conclusion of the operation of the pump 20 and continues until the timer motor 73, now operated through its alternate circuit, has succeeded by the rotation of the shaft 72 of the timer unit 65 in positioning the high point on the disk 71 in contact with the cam follower of the movable contact arm 80. At this point, the cam follower associated with the cam disk 68 reaches the low point thereon causing the movable contact arm 77 to make contact with its fixed contact 84 and closing the circuit through a portion of the mixer valve for supplying mixed water alone to the tub 17 for the performance of the rinsing operation. The circuit is completed through the solenoid V2 of the mixer valve unit from the main power conduit 101 through conductors 103 and 116 to one side of the solenoid and from the other side to the main power supply conductor 102 through conductors 117 and 148, fixed contact 84, movable contact arm 77, conductor 110, fixed contact 111 of the top float switch 112, conductor 114, switch 88 and conductor 115.

After the tub 17 of the automatic washing machine 10 is filled with rinse water, the mixer valve solenoid V2 is deenergized by virtue of the fact that the top float switch 112 breaks contact with its fixed contact 111 when the water reaches the proper level in the tub. The agitator will once again be operated through the energizing of solenoid A. The solenoid A is energized by the closing of the electrical circuit previously described since the cam 70 will have the second low point thereon positioned during this interval in registration with the cam follower on movable contact arm 79. The closing of fixed contact 124 by the top float switch 112 will immediately energize solenoid A.

The duration of the rinsing operation is determined by the aforementioned low point on the cam 70. When the movable contact arm 79 is caused to break contact with its fixed contact 86 by cam 70, the pump solenoid P will be energized in the manner previously described to withdraw

the rinse water from the tub 17 for the reason that the second low point thereon is then in registry with the cam follower for movable contact arm 80. Since the fluid reservoir 33 of the storage means 25 is, as we have seen, not quite filled on the completion of the previous draining operation, the two-way valve 24 will direct a portion of the rinse water to said fluid reservoir until it becomes filled to the proper level.

When the water in the reservoir 33 reaches the maximum fluid level, the float 51 of the fluid operated control mechanism 46 shifts the arm 48 about its pivotal mounting 50 and the link 56 attached thereto causes the arm 57 of the toggle switch 58 to close the circuit energizing the heating element 47 and at the same time lighting the pilot light 63. These functions are accomplished by the closing of contacts 149 and 150 of the toggle switch 58 which closes a direct circuit from the main power conductor 102 through conductors 115 and 151, fixed contacts 149 and 150 of the toggle switch 58, and conductor 152 to one terminal of the heating element 47 while the other terminal is connected through conductors 153 and 154 directly with the main power conduit 101. The conductor 152 connected with the fixed contact 150 of the toggle switch 58 has a branch 155 which completes the circuit simultaneously with that of the heating element 47 through the pilot light 63 to conductor 154 so as to operate the light for the duration of the storage period.

At precisely the same instant that the float 51 closes the toggle switch 58 at the fixed contacts 149 and 150 thereof, the circuit including the fixed contact 142 and 143 of said toggle switch is broken. This operation immediately breaks the circuit supplying current to the solenoid B which controls the two-way valve unit 24. The deenergizing of the solenoid B causes the other outlet thereof to be opened in the manner fully described in our aforementioned application Serial No. 513,138 so as to deliver the remainder of the rinse water discharged by the pump 20 from the tub 17 through the hose connection 28 passing the water to the drain. Thus, no further water will thereafter be delivered to the storage means 25.

The automatic washing machine 10 now continues to perform the remaining operations in the cycle for which the timer unit 65 is designed such, for example, as an additional extracting operation and any other similar steps, while the original supply of hot soapy water is temporarily stored for re-use in the next series of operations to be performed by the automatic washing machine.

Following the completion of the entire cycle of operations, the automatic washing machine 10 is completely shut off until the operator removes the laundered articles from the interior of the tub 17, introduces another batch of laundry and resets the timer unit 65. It will be understood, however, that by virtue of the independence of the electrical circuit for energizing the pilot light 63 and the heating element 47 from the timer unit 65 and the control circuit of the automatic washing machine 10, these elements will continue to function even though the timer 65 has ceased to operate.

It will be readily understood that, if desired, any suitable form of thermostatically controlled or timed safety device may be employed to control the heating element 47 of the storage means 25, in the event that the operator does not for some reason immediately attend the apparatus

after the completion of its cycle of operation. Thus, a suitable automatically operable switch or the like (not shown) which will react to the water temperature, for example, may be introduced into the circuit in series with the heating element 47 for shutting off the electrical current when the water in the fluid reservoir 37 of the storage means 25 has reached a predetermined temperature thereby preventing overheating and consequent waste of electrical current.

When the operator resets the timer 65 for the next series of operations of the automatic washing machine 10, the mixer valve associated therewith will not deliver water to the tub 17 since it has been rendered inoperative by virtue of the fact that the switch 61 associated with the storage means 25 is in the position indicated in dotted lines in Figure 6. However, by reason of the fact that the fixed contact 126 makes contact with the arm 119 of the switch 61, an electrical circuit is completed through the motor 42 for actuating the pump 41 of the storage means 25 to withdraw the water through the outlet 38 in the base of the fluid reservoir 33.

The circuit for operating the motor 42 is completed from the main power supply conduit 101 through the conductors 154 and 156 to one side of said motor and from the other side thereof through conductor 157, fixed contact 126, movable contact arm 119, conductor 120, fixed contact 85 (which will once again be in contact with its movable contact arm 78 as shown), conductors 121 and 110, fixed contact 111 of the top float switch 112, conductor 114, switch 88 and conductor 115 to the main power supply conduit 102.

The pump 41 will operate to drain all of the water out of the fluid reservoir 33 through the hose connection 43 and once again restore it to the tub 17 of the automatic washing machine 10 for the repetition of the same series of operation as were carried out in the previously described cycle. At any time that the operator should desire to cause the soapy water to be discharged to the drain, it is only necessary to trip the switch 61 of the storage means 25 at any interval in the cycle of operations prior to the functioning of the pump 20 on the automatic washing machine 10. The switch arms 107, 119 and 125 of the switch 61 will thereafter be in the position shown in full lines in Figure 6 of the drawings and the solenoid B for the two-way valve 24 will not be energized by the control circuit of the apparatus, and therefore, it will direct all of the water in and passing through the tub 17 of the automatic washing machine 10 through the hose connection 28 to the drain.

It will thus be apparent that the apparatus provides a highly efficient and completely automatic means for accomplishing a series of laundering operations with the use of a minimum quantity of hot water and detergents for cleansing the articles to be laundered.

It will, of course, be understood that various details of construction may be varied through a wide range without departing from the principles of this invention and it is, therefore, not the purpose to limit the patent granted hereon otherwise than necessitated by the scope of the appended claims.

We claim as our invention:

1. In an automatic washing machine having a main tub in which the cycle of operation is carried out, cycling means for controlling sequentially a series of operations of said machine, a

storage tank adjacent said tub, a pump disposed to remove liquid from said tub, a valve in the discharge line of said pump having a pair of passages, one leading to a drain and the other leading to said storage tank, said pump being energized by said cycling means to transfer liquid from said tub to said tank, a float valve disposed in said storage tank adapted to acutate said valve for diverting to the drain the flow of liquid being pumped to said storage tank when the liquid in the tank reaches a predetermined level.

2. In an automatic washing machine having a main tub in which the cycle of operation is carried out, cycling means for controlling sequentially a series of operations of said machine, a storage tank adjacent said tub, a first pump disposed to remove liquid from said tub, a valve in the discharge line of said pump having a pair of passages, one leading to a drain and the other leading to said storage tank, said pump being energized by said cycling means to transfer liquid from said tub to said tank, a float valve disposed in said storage tank adapted to actuate said valve for diverting to the drain the flow of liquid being pumped to said storage tank when the liquid in the tank reaches a predetermined level and a second pump adapted to transfer liquid from said storage tank to the main tub, said second pump being energized by said cycling means automatically when the new washing cycle is begun.

3. In an automatic washing machine having a main tub in which the cycle of operation is carried out, cycling means for controlling sequentially a series of operations of said machine, a storage tank adjacent said tub, a heating element disposed in said storage tank to maintain a desired temperature level of the fluid when the fluid is stored therein, a pump disposed to remove fluid from said tub, a valve in the discharge line of said pump having a pair of passages, one leading to a drain and the other to said storage tank, said pump being energized by said cycling means to transfer fluid from said tub to said tank, a float valve disposed in said storage tank adapted to acutate said valve for diverting to the drain the flow of fluid being pumped to said storage tank when the fluid in the tank reaches a predetermined level, said float also actuating the switch of said heater element, thereby to maintain the temperature of the fluid stored in said storage tank at an elevated temperature.

4. In an automatic washing machine having a main tub in which the cycle of operation is carried out, cycling means for controlling sequentially a series of operations of said machine, a storage tank adjacent said tub, a heating element disposed in said storage tank to maintain a desired temperature level of the fluid when the fluid is stored therein, a pump disposed to remove fluid from said tub, a valve in the discharge line of said pump having a pair of passages, one leading to a drain and the other to said storage tank, said pump being energized by said cycling means to transfer fluid from said tub to said tank, a float valve disposed in said storage tank adapted to acutate said valve for diverting to the drain the flow of fluid being pumped to said storage tank when the fluid in the tank reaches a predetermined level, said float also actuating the switch of said heater element, thereby to maintain the temperature of the fluid stored in said storage tank at an elevated temperature, said float also energizing a signaling

13

means for indicating the presence of fluid in
said storage tank.
